Oil Company, Incorporated, a corporation of
New York

Original application June 27, 1945, Serial No.
601,759. Divided and this application August
17, 1946, Serial No. 691,372

11 Claims. (Cl. 260—329)

1

This invention relates to the manufacture of alkyl derivatives of thiophene, and is more particularly concerned with a process for producing alkyl derivatives of thiophene from aliphatic hydrocarbons containing five and six carbon atoms.

Methyl thiophene and dimethyl thiophene as well as thiophene are well known compounds and occur, ordinarily, in the toluene, xylene and benzene fractions, respectively, of coal tar distillates. The amounts of methyl thiophene and of dimethyl thiophene usually present in the crude toluene and xylene fractions respectively, are of the order of about 0.5%. The close proximity of the boiling points of thiophene and benzene, of methyl thiophene and toluene, and of dimethyl thiophene and xylene, renders the complete separation and recovery of these compounds from the corresponding fractions, by fractional distillation, a somewhat difficult operation. Consequently, commercial benzene normally contains traces of thiophene, and commercial toluene and xylene contain traces of methyl thiophene and of dimethyl thiophene, respectively. However, since thiophene and the alkyl thiophenes are amenable to sulfonation much more readily than benzene, toluene and xylene, thiophene and the alkyl thiophenes can be removed from benzene, toluene and xylene in the form of their sulfonates, by repeated treatments with concentrated sulfuric acid. This, of course, is an expensive operation.

Thiophene has been synthesized in a number of ways. In accordance with the syntheses of the prior art, acetylene has constituted a preferred source of thiophene. Thus, it has been proposed to produce thiophene by reacting acetylene with pyrites, with hydrogen sulfide in the presence of catalytic material, with sulfur in the presence or absence of catalytic material, and with carbon disulfide. Other syntheses proposed have involved the reaction of other hydrocarbons with sulfur or hydrogen sulfide in the presence of various catalytic materials. Thiophene has been produced also from butyl mercaptan by dehydrogenation and cyclization, by cyclization of other organic compounds, by interchange of hetero-atoms in heterocyclic compounds, etc. It must be noted, however, that the yields of thiophene in all of these syntheses generally, have been uniformly poor, in some cases only traces of thiophene or derivatives thereof being produced.

The inherent chemical character of thiophene and of alkyl derivatives of thiophene, indicates a potentially wide use of these compounds in industrial applications; however, the costly na-

2

ture of the methods of separating and recovering thiophene and alkyl thiophenes from crude benzene, toluene and xylene, and the small yields of thiophene obtained in the proposed syntheses, have somewhat limited the use of these compounds commercially, the only present outlets of any consequence, being the drug and dye fields.

Various attempts have been made to provide cheap and commercially feasible processes for producing thiophene; but and as noted hereinbefore, processes embodying the methods known to the prior art, have suffered from two disadvantages, the first being the availability and consequently, the cost of the charging stocks, and the second being the magnitude of the yields of thiophene achieved. Thus, and as is well known to those familiar with the art, when the charge stock of a given process has been readily available and its cost, therefore, has been relatively low, the yields of thiophene have been small; on the other hand, when the yields have been high, the cost of the charge stock has been high.

In the search for readily available and cheap charge stocks to synthesize organic compounds generally, butane and heptane have been reacted with sulfur. These reactions were carried out to determine what compounds would be formed and not for the express purpose of synthesizing thiophene or alkyl thiophenes. However, not more than a mere trace of thiophene and no alkyl thiophene were obtained. [Baker and Reid, Jl. Am. Chem. Soc., vol. 51, p. 1566 (1929).]

A copending application, Serial Number 601,758, filed June 27, 1945, is directed to a process for manufacturing thiophene, which comprises separately preheating sulfur and one or more normal aliphatic hydrocarbons containing four carbon atoms, to temperatures such that by combining the preheated sulfur and the preheated hydrocarbon material, will give a mixture having a temperature varying between about 850° F. and about 1400° F., mixing the preheated sulfur and hydrocarbon material, maintaining the temperature of the mixture at temperatures in excess of about 850° F. for a period of time of at least about 0.01 second, and reducing the temperature of the mixture to less than about 850° F.

55 We have discovered that alkyl derivatives of thiophene may be produced in substantial amounts, by reacting separately preheated aliphatic hydrocarbons containing five or six carbon atoms, with separately preheated sulfur at elevated temperatures.

We have now found that methyl thiophene may be obtained by reacting separately preheated aliphatic hydrocarbons containing five carbon atoms, with separately preheated sulfur at elevated temperatures, and that dimethyl thiophene and ethyl thiophene may be obtained by reacting separately preheated aliphatic hydrocarbons containing six carbon atoms, with separately preheated sulfur at elevated temperatures.

Accordingly, it is an object of the present invention to provide a cheap process for producing alkyl derivatives of thiophene. Another object is to provide a cheap and readily available source of alkyl derivatives of thiophene. A further object is to provide a process for producing alkyl derivatives of thiophene that is commercially feasible. A more specific object is to provide a process for obtaining high yields of methyl thiophene, ethyl thiophene and dimethyl thiophene from aliphatic hydrocarbons containing five and six carbon atoms. A very important object is to afford a process capable of carrying out the above objects by reacting separately preheated aliphatic hydrocarbons containing five or six carbon atoms, with separately preheated sulfur at elevated temperatures.

Other objects and advantages of the present invention will become apparent to those skilled in the art from the following description taken in conjunction with the drawing, in which the single figure represents a diagrammatic illustration of a plant for practicing the process of our invention.

Broadly stated, our invention provides a process for manufacturing alkyl derivatives of thiophene, which comprises separately preheating sulfur and one or more aliphatic hydrocarbons containing five or six carbon atoms, to temperatures such that by combining the sulfur and hydrocarbon material, will give a mixture having a temperature in excess of about 850° F., mixing the preheated sulfur and the preheated hydrocarbon material, reacting the preheated sulfur and the preheated hydrocarbon material at temperatures in excess of about 850° F. for a period of time of at least about 0.01 second, and reducing the temperature of the mixture to less than about 850° F.

A feature of the process of the present invention is that with the exception of hydrogen sulfide, alkyl thiophenes are the principal individual sulfur-containing compounds obtained. A tar, probably a mixture of complex hydrocarbon polysulfides and/or mercaptans containing about 75% sulfur is also produced. The sulfur in this tar can be recovered and recycled. Carbon disulfide is also formed, but only in small amounts. The hydrogen sulfide obtained may be regenerated almost quantitatively back to sulfur for use in the process, by a very inexpensive treatment, such as incomplete combustion into water and sulfur. The sulfur in the tar may be recovered by burning the tar to produce sulfur dioxide. The sulfur dioxide can then be reacted with hydrogen sulfide to produce sulfur.

Another feature of the process of the present invention is that the materials in the charge, i. e., aliphatic hydrocarbons containing five and six carbon atoms and sulfur, are cheap and plentiful. Generally speaking, any aliphatic hydrocarbon having five or six carbon atoms and containing at least four carbon atoms in a chain, is suitable for the process of our invention. The aliphatic hydrocarbons may be derived from any suitable source, as is well known in the art, and

may consist, for example, in the production of methyl thiophene, either of pentane or isopentane or pentenes or isopentenes or even pentadienes, or mixtures of them. On the other hand, in the manufacture of dimethyl thiophene and/or of ethyl thiophene, the aliphatic hydrocarbon charge may consist either of hexane or isohexane or hexenes or isohexenes or even hexadienes, or mixtures of them. It should be observed, however, that for economical operation of our process, it is preferred not to use a hydrocarbon charge consisting predominantly of pentadienes or hexadienes because of their tendency to polymerize under the conditions of the process.

An important feature of our invention is that in our process the reaction is highly selective. High yields of alkyl derivatives of thiophene are obtained, and they may be recovered from the reaction product in a highly pure state using conventional and readily available fractionating equipment.

A very important feature of the present invention is that it provides a cheap and efficient method of producing alkyl derivatives of thiophene. In our process, no catalysts are employed, thereby avoiding the disadvantages attendant on their use, such as regeneration and replacement problems, as well as the use of special reaction chambers. The process is substantially a one-step process, although as will subsequently be seen, appreciable amounts of pentenes or hexenes and of pentadienes or hexadienes may be found in the effluent from the reaction zone. These may be recycled to the reaction zone for further conversion into alkyl derivatives of thiophene, thereby increasing the overall yields of the desired products. The equipment required is essentially only a pair of corrosion-resistant alloy preheaters, a corrosion-resistant alloy reactor coil and a corrosion-resistant condensing system. The separation of hydrogen sulfide presents few difficulties, since most of it can be removed by suitable stabilizing equipment and the last traces removed by caustic scrubbing or other conventional hydrogen sulfide removal processes.

While relatively large quantities of sulfur are employed, it is nevertheless one of the cheapest and most non-critical chemical reagents. We have found, in the operation of our process, that the relative proportions of sulfur and hydrocarbon material may be varied over wide limits. However, too much sulfur results in poor efficiency in sulfur utilization per pass and favors the complete sulfuration of hydrocarbon material to carbon disulfide. On the other hand, too low a proportion of sulfur lowers the conversion per pass and the ultimate yield by increasing the overall thermal degradation of hydrocarbon material. Best results are obtained using a weight ratio of sulfur to hydrocarbon material varying between about 0.5 and about 4.0, although when pentenes or pentadienes, or hexenes or hexadienes constitute the bulk of the hydrocarbon material in the charge, the lower limit of the weight ratio may be lower than 0.5.

The selectivity of the reaction involved in the process of the present invention depends primarily upon two variables, namely, the reaction temperature at which the aliphatic hydrocarbons containing five or six carbon atoms are contacted with sulfur, and the reaction time or the time during which contact between the reactants is maintained at the reaction temperature.

The limits of operating temperature are fixed by the kinetics of the desired reaction and the

kinetics of possible side reactions. We have found that the reaction temperature may vary between about 850° F. and about 1300° F., and preferably, between about 900° F. and about 1100° F. Below the lower limit of the temperature range, the reaction is so slow as to require a large throughput of sulfur and a higher ratio of hydrocarbon recycle for a fixed amount of end product, therefore detracting from the economics of the operation. Further, the secondary reaction of tar formation consumes a larger proportion of the charge. Above the upper limit of the temperature range, the secondary reaction of degradation of hydrocarbon material in the charge takes precedence, thereby decreasing the yield of desired product. In addition to this, high temperatures favor the formation of carbon disulfide. It must be noted, also, that at these high temperatures, corrosion problems are at a maximum, corrosion increasing perceptibly with increasing temperature.

As expected, we have found that the optimum reaction time depends upon the temperature employed. Generally speaking, other variables remaining constant, the lower the temperature, the longer the reaction time. The reaction or contact time and the reaction temperature are somewhat fixed, one in relation to the other, by the degree of degradation of the hydrocarbon material in the charge, and by the extent of formation of undesirable products, which may be tolerated. Thus, too long a contact time at high temperatures, results in severe cracking of the hydrocarbon material in the charge. The reaction which is highly endothermic, proceeds with extreme speed, the only limitation apparently being the rapidity with which heat can be supplied to the reaction mixture. The lower limit of the range of reaction time is fixed, therefore, by the engineering problem of heat transfer and by mechanical limitations such as allowable pressure drop across the reactor. Too long a reaction time at temperatures in the neighborhood of the lower limit of the temperature range, results in lower overall yields of alkyl thiophenes due to increased formation of heavy tar. On the other hand, too short a reaction time at temperatures in the neighborhood of the lower limit of the temperature range, results in incomplete reaction. Accordingly, we have found that for best results, the time of reaction is fixed by the reaction temperature.

In view of the foregoing, the criteria to be used in determining optimum operating temperatures within the range 850-1300° F., and reaction times are to choose the degree of conversion desired commensurate with operating cost, such as heat input and equipment costs, bearing in mind that within limits the shorter the reaction time and concordantly, the higher the temperature, the larger the amount of end product which can be realized from a unit of given size per day.

Generally speaking, the relationship between the temperature of reaction and reaction time is not singular with our invention. It is a well established and fairly well understood relationship in numerous reactions. In the present instance, we have found that alkyl thiophenes may be produced by reacting sulfur and aliphatic hydrocarbons containing five and six carbon atoms at a temperature falling within about 850° F. and about 1300° F., for a period of time selected to minimize the yield of secondary reaction products at the selected temperature. Accordingly, for the reaction temperature range of our proc-

ess, i. e., 850° F. to 1300° F., when operating continuously with a reactor coil of suitable size and at a practical charge rate, we have found that the lowest practical limit of the time of reaction is of the order of 0.01 second at about 1300° F. The upper practical limit of reaction time, other variables remaining constant, will correspond to the lower limit of the temperature of reaction and may be of the order of several seconds.

10 Separate preheating of the hydrocarbon reactant and sulfur, and quenching of the reaction mixture are necessary for achieving the somewhat close control of the reaction time at a given reaction temperature. This is very important in the specific reaction producing methyl thiophene or dimethyl thiophene and ethyl thiophene. Without any intention of limiting the scope of the present invention, it is suspected that a number of reactions occur in the reaction between the hydrocarbon reactant and sulfur. In this connection, the following should be noted: cracking of the hydrocarbon reactant destroying the four or more carbon-atom straight-chain structure (the four carbon-atom straight-chain structure being a prerequisite for the formation of the thiophene nucleus); formation of the thiophene nucleus; formation of tar high in sulfur; and formation of carbon disulfide. These reactions compete with one another. We have found that the rates of the formation of lighter hydrocarbons and of the formation of carbon disulfide are somewhat slower than that required for the formation of the thiophene nucleus. Accordingly, a proper control of the reaction time at a given reaction temperature achieved by separate preheating, mixing, heating at a given temperature for a corresponding period of time, and quenching is necessary to produce high yields of methyl thiophene or dimethyl thiophene and ethyl thiophene with limited yields of carbon disulfide and fixed gases due to a limited decomposition of the hydrocarbon reactant. The rate of the reaction producing tar is fairly close to that required for the formation of the thiophene nucleus and, therefore, the control of this reaction is more difficult. Hence, in spite of the separate preheating and ultimate quenching of the reaction mixture, the yields of tar approximate those of methyl thiophene or of dimethyl thiophene and ethyl thiophene.

55 In carrying out the process of the present invention, therefore, it is essential to separately preheat the reactants. Heating the hydrocarbon material and the sulfur together has two undesirable effects. In the first place, at lower temperatures, the reaction producing tar formation is the favored reaction; and in the second place, these heavy products are subsequently cracked in the reactor at the selected reaction temperature, causing undue coking. Tests have shown that when the reactants are heated together up to temperatures within the aforementioned reaction temperature range, tar formation always results, and in such quantities, that the reaction zone is eventually plugged up with a heavy, carbonaceous deposit. Accordingly, it is essential in our process to separately preheat each of the reactants, i. e., the hydrocarbon or the mixture of hydrocarbons constituting the hydrocarbon reactant and sulfur, to such temperatures that when they are brought together, under proper conditions of flow, a temperature falling within the reaction temperature range is achieved, before effecting contact between them. In practice, this is effected ordinarily, by separately preheating

each of the reactants to temperatures within the reaction temperature range.

After the separately preheated hydrocarbon reactant and sulfur are mixed and allowed to react for the reaction time indicated by the operating temperature, the temperature of the reaction mixture is immediately lowered to below 850° F., in practice, appreciably below 850° F., in order to avoid over-reaction in the system after leaving the reactor. This may be accomplished suitably by spraying the effluent of the reactor with a liquid.

As stated hereinbefore, for economical operation of the process, we prefer not to use a hydrocarbon charge consisting predominantly of pentadiene or hexadiene, because of their tendency to polymerize in the preheater with consequent cracking and severe coking in the reactor. However, when pentadiene or hexadiene are used in conjunction with predominant amounts of pentanes and/or pentenes, or with predominant amounts of hexanes and/or hexenes, respectively, or suitable diluents which are inert with respect to sulfur and to other reaction products of the process, for example, nitrogen, carbon disulfide, carbon dioxide, etc., they can be processed satisfactorily to give high yields of alkyl derivatives of thiophene. For effective operation of our process, we have found that pentadienes or hexadienes should constitute a minor proportion of the charge.

In our process, the reaction is effected, preferably, at atmospheric pressure or under sufficient pressure to cause the flow of the reactants through the reactor and auxiliary system, under the desired reaction conditions. Tests have shown that the yields per pass and ultimate yields of methyl thiophene or dimethyl thiophene and ethyl thiophene decrease with increase in pressure. However, even at appreciable pressures, methyl thiophene or dimethyl thiophene and ethyl thiophene are nevertheless produced in substantial amounts. Accordingly, there appears to be nothing critical about pressure as a reaction variable. We have found that best results are obtained when turbulent flow is maintained through the reactor, suitably, a conventional coil-type pipe reactor. With this type of reactor, the desired turbulent flow may be achieved with a pressure drop of about 1 to 20 pounds across the coil, depending upon the size of the pipe and the length of the coil. Turbulent flow promotes heat transfer and assures good mixing of the reacting vapors of sulfur and hydrocarbon material.

Recycling of the unreacted portion of hydrocarbon material in the effluent stream, has been found to be a desirable scheme for increasing the ultimate yield of desired product. This has the same effect as lengthening the reaction time without the attendant and undesirable degradation of hydrocarbon material, referred to hereinbefore. When the paraffinic hydrocarbons are the hydrocarbon reactants, it is suspected that the reaction proceeds stepwise with the formation of the corresponding olefinic hydrocarbons, diolefinic hydrocarbons and finally, alkyl thiophenes, each step causing the formation, simultaneously, of hydrogen sulfide, molecular weight for molecular weight. These reactions occur concurrently and unreacted pentane or hexane as well as pentenes or hexenes and pentadienes or hexadienes are found in the effluent. Only traces of acetylenic hydrocarbons have been found. The hydrocarbons in the effluent serve as recycle stream in the recycling operation. In this connection, it

must be observed that when pentenes or hexenes are the sole constituents of the hydrocarbon reactant, recycling of the hydrocarbons in the effluent is not commercially feasible in view of the high concentration of pentadienes or hexadienes, respectively, in the recycle stock. However, and as stated hereinbefore, pentanes or hexanes, or other suitable diluents may be added to the recycle stocks and the latter processed to give high yields of alkyl derivatives of thiophene.

Accordingly, a most important feature of our process, is that it is flexible, it being possible to produce pentenes or hexenes as well as pentadienes or hexadienes from the pentane or hexane, or pentadienes or hexadienes from pentenes or hexenes, respectively, in addition to alkyl thiophenes.

A plant for practicing the process of our invention with respect to the manufacture of methyl thiophene is illustrated diagrammatically in the drawing. It is understood, of course, that certain modifications of this operating scheme, as well as changes in the type of equipment employed, may be made as long as the essential requirements of the process are maintained, as will be obvious to those skilled in the art, once the conditions of the process, with which this invention is concerned, are clearly understood.

Referring now more particularly to the drawing, pentane is pumped from a storage sphere 4 by a pump 5, to a preheater coil 6. Molten sulfur is pumped from a storage tank 1 by a pump 2, to a preheater coil 3. The preheated vapors of pentane and sulfur are mixed at a point 7 prior to introduction into the reactor, and are then sent through a reactor coil 8. The preheaters 3 and 6 and the reactor 8 may each be in separate furnaces, as shown, may be of different lengths to produce the desired preheating temperatures and reaction temperatures. As stated hereinbefore, for economical operation of the process of the present invention, short reaction times must be used. This requires rapid mixing of the reactants and rapid heat transfer to the reaction mixture. The reaction products enter a spray chamber 9 where they are quenched to a temperature of about 300° F., by spraying suitably with crude methyl thiophene or some other liquid product of the process. The quenched reaction products subsequently are passed into a tar-separator 10, wherein tar separates out and is sent to a sulfur-recovery plant 18. The reaction products free of the bulk of the tar, go to a filter 11, to separate the tar mist. A Cottrell precipitator may be used as the mist collector if desired. The filtered products are then passed into a condensate stripper column 12 where most of the products that are normally liquid are stripped out. This column may be operated as an absorption stripper by using methyl thiophene bottoms as the absorber liquid. The overhead from the condensate stripper column 12, go to a compressor 13 and thence to a column 14 where C₃-hydrocarbon gases, gases lighter than C₃-hydrocarbons, and hydrogen sulfide are removed as overhead and sent to the sulfur-recovery plant 18. The bottoms from the column 14, consisting of C₄-hydrocarbons and materials having boiling points higher than C₄-hydrocarbons, are passed into a column 15 where C₄-hydrocarbons are obtained as overhead. The bottoms from column 15, consisting of C₅-hydrocarbons and materials having boiling points higher than C₅-hydrocarbons together with the liquid bottoms from the condensate stripper column 12 are passed into a column 20 where C₆-hydrocar-

bons are obtained as overhead, combined with the overhead from the debutanizer column 15, and recirculated through a meter 16 to the preheater 6, and thus returned to the process as recycle stock. The bottoms from the column 20 are sent to the carbon disulfide tower 17. Carbon disulfide is taken off as overhead from the tower 17 and sent to storage, while the bottoms from the tower 17 are passed into a thiophene tower 18 where thiophene produced as a result of some cracking of C₈-hydrocarbons into C₄-hydrocarbons, is taken as overhead and to storage. The thiophene tower bottoms are passed into a methyl thiophene tower 19 where methyl thiophene is taken as overhead and to storage and methyl thiophene tower bottoms taken to storage to be used in the condensate stripper column 12 and/or as a spray in the spray chamber 8.

In a typical operation, the hydrocarbon material charged to the preheater coil 6 is made up of a normal pentane cut containing varying amounts of pentenes, obtained from a cracking unit for the conversion of gas oil into gasoline. Sulfur is charged to the preheater 3, in amounts to produce a mixture at 7 having a weight ratio of sulfur to butane cut, of about 1.0 and the charge rates are adjusted to give a reaction time of about 0.06 second in the reactor coil 8 at temperatures of 1100° F.

The following detailed examples are for the purpose of illustrating modes of producing alkyl thiophenes in accordance with our invention, it being clearly understood that the invention is not to be considered as limited to the specific manipulations and conditions set forth hereinafter.

Example 1

834 grams of isopentane were charged into a preheater at the rate of 40 grams per minute and heated to a temperature of 1080° F. 583 grams of sulfur were charged to a separate preheater at a rate of 28 grams per minute and heated to a temperature of 1080° F. The two streams were sent through a mixing nozzle and thence through a baffled tube reactor of 50 c. c. volume constructed of 27% chromium stainless steel maintained at a temperature of 1200° F. The reaction product was quenched with a water spray, passed through a small Cottrell precipitator to remove tar mist, and scrubbed through a hot countercurrent caustic tower. The liquid product was cooled, condensed and separated in a water cooler and ice trap. 753 grams of liquid were recovered. Fractionation of the liquid through a 15 theoretical-plate column gave 88 grams of a product having a boiling range of 107-115° C. Physical measurements and chemical tests established this fraction to be methyl thiophene.

Example 2

The run described in Example 1 was repeated with the exception that 592 grams of normal hexane and 506 grams of sulfur were charged. 521 grams of liquid product were obtained which on distillation, gave 30 grams of a fraction boiling at 135-138° C. Physical measurements and chemical tests established that this fraction was a mixture of dimethyl thiophene and ethyl thiophene.

This application is a division of copending application, Serial Number 601,759, filed June 27, 1945, which in turn is a continuation-in-part of copending application, Serial Number 556,438, filed September 29, 1944.

The present invention may be embodied in

other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

We claim:

1. A process for producing dimethyl thiophene and ethyl thiophene, which comprises separately preheating sulfur and a hydrocarbon selected from the group consisting of hexanes, hexenes, and hexadienes, having at least four carbon atoms in a straight chain, to temperatures such that combining said sulfur and said hydrocarbon will give a reaction mixture having a temperature varying between about 850° F. and about 1300° F.; mixing the preheated sulfur and the preheated hydrocarbon; reacting said preheated sulfur with said preheated hydrocarbon at a reaction temperature varying between 850° F. and about 1300° F. to produce a dimethyl thiophene and ethyl thiophene-containing mixture; and reducing the temperature of said dimethyl thiophene and ethyl thiophene-containing mixture to less than 850° F.
2. A process for producing dimethyl thiophene and ethyl thiophene, which comprises separately preheating sulfur and a hydrocarbon selected from the group consisting of hexanes, hexenes and hexadienes, having at least four carbon atoms in a straight chain, to temperatures such that combining said sulfur and said hydrocarbon will give a reaction mixture having a temperature varying between about 900° F. and about 1100° F.; mixing the preheated sulfur and the preheated hydrocarbon; reacting said preheated sulfur with said preheated hydrocarbon at a reaction temperature varying between about 900° F. and about 1100° F. to produce a dimethyl thiophene- and ethyl thiophene-containing mixture; and reducing the temperature of said dimethyl thiophene- and ethyl thiophene-containing mixture to less than 850° F.
3. A process for producing dimethyl thiophene and ethyl thiophene, which comprises separately preheating sulfur and a hexane having at least four carbon atoms in a straight chain, to temperatures such that combining said sulfur and said hexane will give a reaction mixture having a temperature varying between about 850° F. and about 1300° F.; mixing the preheated sulfur and the preheated hexane; reacting said preheated sulfur with said preheated hexane at a reaction temperature varying between 850° F. and about 1300° F. for a period of time selected to minimize the yields of hydrocarbons containing less than four carbon atoms per molecule and carbon disulfide at said reaction temperature, to produce a dimethyl thiophene- and ethyl thiophene-containing mixture; and reducing the temperature of said dimethyl thiophene- and ethyl thiophene-containing mixture to less than 850° F.
4. A process for producing dimethyl thiophene and ethyl thiophene, which comprises separately preheating sulfur and a hexane having at least four carbon atoms in a straight chain, to temperatures such that combining said sulfur and said hexane will give a reaction mixture having a temperature varying between about 900° F. and about 1100° F.; mixing the preheated sulfur and the preheated hexane; reacting said preheated sulfur with said preheated hexane at a reaction temperature varying between about 900° F. and about 1100° F. for a period of time selected to

minimize the yields of hydrocarbons containing less than four carbon atoms per molecule and carbon disulfide at said reaction temperature, to produce a dimethyl thiophene and ethyl thiophene-containing mixture; and reducing the temperature of said dimethyl thiophene and ethyl thiophene-containing mixture to less than about 850° F.

5. The process which comprises separately preheating sulfur and a hexane having at least four carbon atoms in a straight chain, to temperatures such that combining said sulfur and said hexane will give a reaction mixture having a temperature varying between about 850° F. and about 1300° F.; mixing the preheated sulfur and the preheated hexane; reacting said preheated sulfur with said preheated hexane at a reaction temperature varying between 850° F. and about 1300° F. for a period of time selected to minimize the yields of hydrocarbons containing less than four carbon atoms per molecule and carbon disulfide at said reaction temperature, to yield a product containing thiophene, methyl thiophene, dimethyl thiophene, ethyl thiophene, normal butane, normal butenes, butadienes, and pentanes, pentenes, pentadienes, hexanes, hexenes and hexadienes, containing at least four carbon atoms in a straight chain; reducing the temperature of said product to less than 850° F.; separating normal butane, normal butenes, butadienes, and pentanes, pentenes, pentadienes, hexanes, hexenes and hexadienes, containing at least four carbon atoms in a straight chain from said product; and recycling said normal butane, normal butenes, butadienes, and pentanes, pentenes, pentadienes, hexanes, hexenes and hexadienes, containing at least four carbon atoms in a straight chain to the process.

6. A process for producing dimethyl thiophene and ethyl thiophene, which comprises separately preheating sulfur and a hexene having at least four carbon atoms in a straight chain, to temperatures such that combining said sulfur and said hexene will give a reaction mixture having a temperature varying between about 850° F. and about 1300° F.; mixing the preheated sulfur and the preheated hexene; reacting said preheated sulfur with said preheated hexene at a reaction temperature varying between 850° F. and about 1300° F. for a period of time selected to minimize the yields of hydrocarbons containing less than four carbon atoms per molecule and carbon disulfide at said reaction temperature, to produce a dimethyl thiophene- and ethyl thiophene-containing mixture; and reducing the temperature of said dimethyl thiophene- and ethyl thiophene-containing mixture to less than 850° F.

7. A process for producing dimethyl thiophene and ethyl thiophene, which comprises separately preheating sulfur and a hexene having at least four carbon atoms in a straight chain, to temperatures such that combining said sulfur and said hexene will give a reaction mixture having a temperature varying between about 900° F. and about 1100° F.; mixing the preheated sulfur and the preheated hexene; reacting said preheated sulfur with said preheated hexene at a reaction temperature varying between about 900° F. and about 1100° F. for a period of time selected to minimize the yields of hydrocarbons containing less than four carbon atoms per molecule and carbon disulfide at said reaction temperature, to produce a dimethyl thiophene and ethyl thiophene-containing mixture; and reducing the temperature of said dimethyl thiophene and ethyl

thiophene-containing mixture to less than about 850° F.

8. The process which comprises separately preheating sulfur and a hexene having at least four carbon atoms in a straight chain, to temperatures such that combining said sulfur and said hexene will give a reaction mixture having a temperature varying between about 850° F. and about 1300° F.; mixing the preheated sulfur and the preheated hexene; reacting said preheated sulfur with said preheated hexene at a reaction temperature varying between 850° F. and about 1300° F. for a period of time selected to minimize the yields of hydrocarbons containing less than four carbon atoms per molecule and carbon disulfide at said reaction temperature, to yield a product containing thiophene, methyl thiophene, dimethyl thiophene, ethyl thiophene, normal butane, normal butenes, butadienes, and pentanes, pentenes, pentadienes, hexanes, hexenes and hexadienes, containing at least four carbon atoms in a straight chain; reducing the temperature of said product to less than 850° F.; separating normal butane, normal butenes, butadienes, and pentanes, pentenes, pentadienes, hexanes, hexenes and hexadienes, containing at least four carbon atoms in a straight chain from said product; and recycling said normal butane, normal butenes, butadienes, and pentanes, pentenes, pentadienes, hexanes, hexenes and hexadienes, containing at least four carbon atoms in a straight chain to the process.

9. A process for producing dimethyl thiophene and ethyl thiophene, which comprises separately preheating sulfur and a hydrocarbon mixture containing a minor proportion of a hexadiene having at least four carbon atoms in a straight chain, to temperatures such that combining said sulfur and said hydrocarbon mixture will give a reaction mixture having a temperature varying between about 850° F. and about 1300° F.; mixing the preheated sulfur and the preheated hydrocarbon mixture; reacting said preheated sulfur with said preheated hydrocarbon mixture at a reaction temperature varying between 850° F. and about 1300° F. for a period of time selected to minimize the yields of hydrocarbons containing less than four carbon atoms per molecule and carbon disulfide at said reaction temperature, to produce a dimethyl thiophene- and ethyl thiophene-containing mixture; and reducing the temperature of said dimethyl thiophene- and ethyl thiophene-containing mixture to less than 850° F.

10. A process for producing dimethyl thiophene and ethyl thiophene, which comprises separately preheating sulfur and a hydrocarbon mixture containing a minor proportion of a hexadiene having at least four carbon atoms in a straight chain, to temperatures such that combining said sulfur and said hydrocarbon mixture will give a reaction mixture having a temperature varying between about 900° F. and about 1100° F.; mixing the preheated sulfur and the preheated hydrocarbon mixture; reacting said preheated sulfur with said preheated hydrocarbon mixture at a reaction temperature varying between about 900° F. and about 1100° F. for a period of time selected to minimize the yields of hydrocarbons containing less than four carbon atoms per molecule and carbon disulfide at said reaction temperature, to produce a dimethyl thiophene and ethyl thiophene-containing mixture; and reducing the temperature of said di-

methyl thiophene and ethyl thiophene-containing mixture to less than about 850° F.

11. The process which comprises separately preheating sulfur and a hydrocarbon mixture containing a minor proportion of a hexadiene having at least four carbon atoms in a straight chain, to temperatures such that combining said sulfur and said hydrocarbon mixture will give a reaction mixture having a temperature varying between about 850° F. and about 1300° F.; mixing the preheated sulfur and the preheated hydrocarbon mixture; reacting said preheated sulfur with said preheated hydrocarbon mixture at a reaction temperature varying between 850° F. and about 1300° F. for a period of time selected to minimize the yields of hydrocarbons containing less than four carbon atoms per molecule and carbon disulfide at said reaction temperature, to yield a product containing thiophene, methyl thiophene, dimethyl thiophene, ethyl thiophene, normal butane, normal butenes, butadienes, and pentanes, pentenes, pentadienes, hexanes, hexenes, and hexadienes, containing at least four

5 carbon atoms in a straight chain; reducing the temperature of said product to less than 850° F.; separating normal butane, normal butenes, butadienes, and pentanes, pentenes, pentadienes, hexanes, hexenes, and hexadienes, containing at least four carbon atoms in a straight chain from said product; and recycling said normal butane, normal butenes, butadienes, and pentanes, pentenes, pentadienes, hexanes, hexenes and hexadienes, containing at least four carbon atoms in

10 a straight chain to the process.

Certificate of Correction

Patent No. 2,450,687.

October 5, 1948.

HERBERT E. RASMUSSEN ET AL.

It is hereby certified that errors appear in the printed specification of the above numbered patent requiring correction as follows:

Column 7, line 7, after the word "below" insert *about*; column 8, line 38, after the syllable "naces" and before the comma insert *if desired, or, if in the same furnaces*; and that the said Letters Patent should be read with these corrections therein that the same may conform to the record of the case in the Patent Office.

Signed and sealed this 10th day of May, A. D. 1949.
